UNITED STATES PATENT OFFICE.

CHESTER A. TEITS, OF AKRON, OHIO.

ETCHING-MACHINE.

1,233,524.

Specification of Letters Patent. Patented July 17, 1917.

Application filed November 7, 1916. Serial No. 130,004.

To all whom it may concern:

Be it known that I, CHESTER A. TEITS, a citizen of the United States, residing at Akron, in the county of Summit and State 5 of Ohio, have invented certain new and useful Improvements in Etching-Machines, of which the following is a specification.

This invention relates to new and useful improvements in etching machines and has 10 for its primary object, the provision of a machine of this character which will be of improved construction and operation comparatively inexpensive and highly efficient in use.

15 Another object of the invention resides in the provision of an etching machine in which air will be employed for forcing the acid upon the plate within the tank, thereby causing a rapid and even action of the acid 20 upon the plate, a suitable hood being provided for carrying away the fumes from the acid.

25 The invention for a further object, contemplates the provision of an etching machine of the above stated character in which the carriage carrying the air tubes may be reciprocated upon the tank as the air is forced through the tubes and directed toward the plate resting in the bottom of the 30 acid tank below the acid level.

A still further object of the invention resides in the provision of an etching machine of the above stated character in which the fan employed for supplying air to the 35 depending air tubes of the carriage is operated by the same means as employed for driving the carriage over the tank.

With these and other objects in view, as 40 will appear as the nature of the invention is better understood, the invention consists in the novel combination and arrangement of coöperating elements hereinafter more specifically set forth, shown in the drawings and pointed out in the appended 45 claims.

In the accompanying drawings forming a part of this application and in which like designating characters of reference refer to corresponding parts throughout the several 50 views.

Figure 1 is a plan view of the complete device with the hood removed.

Fig. 2 is a vertical longitudinal section with parts broken away and parts shown in 55 elevation, and,

Fig. 3 is a detail transverse vertical sec-

tion, substantially on the plane of line 3—3 of Fig. 2, looking in the direction indicated by the arrows.

Referring more particularly to the drawings, 1 designates the acid tank which is mounted upon a suitable support 2 carried in the corner frame members 3, which latter are preferably formed of angle iron, while the tank 1 is formed of some acid 60 proof composition. The corner members 3 also carry a lower supporting frame 4, upon which the base 5 is mounted to support a motor 6 and fan casing 7, which latter 65 incloses a conventional form of air fan, upon the projecting end of the shaft 8 of which is mounted a belt wheel 9 adapted to be driven by the belt 10 from the belt wheel 11 on the shaft 12 of the motor 6.

An air conducting pipe 13 is extended 75 from the fan casing 7 to the air distributing pipe 14, upon the opposite ends of which are mounted the flexible pipes or hose sections 15 leading to the air distributing pipes 16 of a longitudinally reciprocable 80 carriage which includes carriage sections 17.

The air distributing pipes 16 form one end of the distributing carriage sections 17 and are connected with the opposite ends thereof by means of the transverse air pipes 85 18, from which are extended the depending air discharge pipes 19, the open lower ends of which extend into the acid 20 positioned in the acid tank 1. The lower ends of the air discharged pipes 19 are spaced sufficiently 90 above the bottom of the tank 1, however, to avoid the upper surface of a plate resting upon the bottom of the same, as the carriage reciprocates longitudinally of the tank 1, as will be clearly understood. 95

The carriage sections 17 are mounted upon the carriage base members 21 which are provided in their under faces with grooves 22 to receive the upper edges of the tank sides 23, whereby the carriage may be properly 100 guided in its movement over the tank 1. The carriage base members 21 are provided with upstanding flanges 24 having suitable perforations to receive the securing members employed for fastening the adjustable carriage sections 17 in proper adjusted position with respect to one another.

Secured to the carriage base members 21 and depending from the same, upon opposite sides of the tank 1, are the bracket members 26, which are shown as being of triangular form and in the lower corners of 110

which, is mounted the rod 27, which is rigid with the bracket members 26 and has a depending member 28, to which is pivoted, as shown at 29, one end of the pitman arm 30, the opposite end of which is eccentrically mounted upon the disk 31. The disk 31 is mounted upon the stub shaft 32 supported in the bracket arm 33 projecting from one of the corner supports 3. The stub shaft 32 also carries a gear 34 adapted to be driven by a larger gear 35 mounted upon a second stub shaft 36, supported in the depending end of the bracket arm 33. The larger gear 35 is adapted to be driven by the gear 37 mounted upon the main shaft 12 of the motor 6.

In order to carry off the acid fumes, I provide a hood 38, which is mounted over the tank 1 and has a fume discharge pipe 39 extended from the opening 40 in the uppermost portion of the inclined top 41 of said hood 38. It will therefore be seen that all fumes from the acid may be readily carried away.

It will be apparent that upon operation of the motor 6, the carriage will be reciprocated longitudinally upon the tank 1 with the depending or discharge pipes 19 riding over the plate in the acid 20 and from end to end of said plate while at the same time the fan in the fan casings 7 is causing a discharge of air from the lower ends of the air discharge pipes 19 to agitate the acid 20 and force the same against the upper surface of the plate.

While the form of the invention shown and described, is what is believed to be a preferred embodiment thereof it is nevertheless to be understood that minor changes therein in the details of construction and arrangement of parts may be resorted to within the scope of the appended claims without departing from the spirit of the invention.

What I claim is:—

1. A machine of the character described, a receptacle, a carriage movable longitudinally of the receptacle, a plurality of horizontally disposed tubes carried by the carriage, a plurality of vertically disposed tubes carried by the horizontally disposed tubes and having communication therewith, means for transmitting motion to the carriage to cause the same to move longitudinally over the receptacle, and means for forcing air through the tubes.

2. In an etching machine a supported receptacle, base members movable back and forth over the receptacle, air distributing pipes carried thereby, horizontally disposed pipes carried by the air distributing pipes and communicating with the same, means for moving the base members back and forth over the receptacle, and means for forcing air through the tubes.

3. In an etching machine, a supported receptacle, air distributing pipes movable back and forth over the receptacle, means for imparting such motion to the air distributing pipes, a plurality of communicating pipes carried by the air distributing pipes having communication with the receptacle, vertically disposed air supply pipes communicating with the distributing pipes, and a source of air supply communicating with the last mentioned pipes.

4. In a machine of the character described a supported receptacle for containing a liquid, base members movable back and forth over the receptacle, air distributing pipes carried thereby, means connecting the air distributing pipes whereby the same may be adjusted longitudinally with respect to each other, a plurality of tubes communicating with the air distributing pipes the ends of which being adapted to be submerged in the liquid contained in the receptacle, and means for forcing air through the pipes.

5. In an operating machine a supported receptacle, air distributing pipes operatively connected together and movable back and forth over the receptacle, communicating tubes carried by the air distributing pipes and having communication with the receptacle, vertically extending air supply pipes communicating with the distributing pipes, a source of air supply communicating with the vertically extending pipes, brackets operatively connected with the air distributing pipes, and means operatively connected with the brackets and for imparting a back and forth motion to the air distributing pipes.

6. An etching machine comprising an acid containing tank, a supporting means for said tank, a carriage mounted on said tank and including transverse tubes, air discharge tubes depending from said transverse tubes and extending into the acid in said tank, means for moving said carriage over said tank, means for forcing air into said carriage and discharging the same from said depending tubes, flexible connections between said last mentioned means and said carriage, a motor for driving the last mentioned means and the carriage moving means, and an acid fume discharge hood mounted over said tank.

7. An etching machine comprising an acid containing tank, a supporting frame for said tank, a carriage mounted upon said tank and including base members movable on the sides of said tank, carriage sections supported upon said base members, means for securing said carriage sections in adjusted position with respect to one another, said carriage sections including depending air discharge tubes extending into the acid in said tank, air supplying means for said carriage, flexible connections between said last mentioned means and said carriage, a

holder, connections between said holder and said air supplying means, driving connections between said holder and said carriage, and a hood for said tank.

5 8. A machine of the character described comprising a receptacle for containing liquid, a carriage reciprocable above the receptacle, means for imparting such motion to the carriage, a plurality of communicating horizontal tubes carried by the carriage, vertical tubes communicating with the hori-

zontal tubes and extending within the receptacle, and means for forcing a fluid through the tubes whereby to agitate the liquid contained in the receptacle. 15

In testimony whereof I affix my signature in presence of two witnesses.

CHESTER A. TEITS.
